UNITED STATES PATENT OFFICE

106,215

DESIGN FOR A SHOE

Anthony A. Ryan, Worcester, Mass.

Application August 6, 1937, Serial No. 70,866

Term of patent 3½ years

To all whom it may concern:

Be it known that I, Anthony A. Ryan, a citizen of the United States, residing at Worcester, in the county of Worcester and Commonwealth of Massachusetts, have invented a new, original, and ornamental Design for a Shoe, of which the following is a specification, reference being had to the accompanying drawing, forming a part thereof, in which,

Fig. 1 is a plan view of the shoe showing my new design, and

Fig. 2 is a corresponding view in side elevation.

The dominating feature of my invention resides in a bow arranged to cover the throat of the vamp and to present a V-shaped opening having also a transverse and longitudinally disposed loop.

I claim:

The ornamental design for a shoe, substantially as shown and described.

ANTHONY A. RYAN.
